UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

PRESSER FOOT FOR SEWING MACHINES.

1,404,704.

Specification of Letters Patent. Patented Jan. 24, 1922.

Application filed May 3, 1919. Serial No. 294,391.

To all whom it may concern:

Be it known that I, ALBERT H. DE VOE, a citizen of the United States, residing at Westfield, in the county of Union and State 5 of New Jersey, have invented certain new and useful Improvements in Presser Feet for Sewing Machines, of which the following is a specification, reference being had therein to the accompanying drawings.

10 This invention relates to presser-feet for sewing machines and aims to improve details of construction thereof especially for the type of foot employed in stitching at widely spaced intervals heavy material, such

15 as stiff canvas, wherein it is desirable to hold the work with the same pressure immediately adjacent each of the spaced needles in order that the feed-dogs may advance the material at the same rate past each needle.

20 The construction briefly described comprises a pair of sole portions universally connected to a tilting lever which is fulcrumed to the lower end of a presser-bar and has the sole portions held by links in 25 breastwise relation while the outside heels of the sole portions are yieldingly urged downward upon the work.

The invention is illustrated in the accompanying drawings, in which Fig. 1 represents 30 the presser-foot partially sectioned in front elevation. Fig. 2 represents a top plan view thereof and Fig. 3 represents a sectional end elevation.

The presser-foot is illustrated as it has 35 been embodied in metal applied to a two-needle chain-stitch machine but obviously it is capable of use with a wide variety of stitch-forming mechanism and with any number of needles.

40 In the drawings at the lower end of the presser-bar 1 a cross-bar 2 is secured by a fastening screw 3. The cross-bar 2 is provided with substantially vertical and horizontal flat surfaces 4 and 5, respectively, which as shown in Fig. 3 are disposed in 45 planes parallel and at right angles respectively to the axis of the presser-bar. A tilting lever 6 is fulcrumed on the conical headed bolt 7, which is locked by the nut 8, the rear face of this lever 6 being guided by 50 the flat surface 4 of the cross-member 2. The tilting lever 6 is provided with axially

aligned sockets receiving pins 9 adjustment of which laterally is permitted by the set-screws 10. At their free projecting ends the pins 9 are provided with split spherical 55 sockets 11 which embrace the ball-studs 12 threaded centrally into the sole portions 13.

Needle-holes 14 are provided in the sole portions at suitable intervals. Rearwardly each of the sole portions has secured thereto 60 bearing lugs 15 adjustably sustaining pins 16 around which are coiled springs 17 whose opposite ends are anchored to the pins 16 and to the relatively fixed split spherical 65 sockets 11, respectively, and normally urge the heel of the sole portions downwardly. Lugs 17' on each sole portion beneath the split sockets 11, limit the action of springs 17 and a slot 16' in the end of each rod 16 permits ready tensioning of the springs. 70

In order to hold the sole portions 13 abreast of each other and against turning about their ball-and-socket connections with the tilting lever 6, ball-studs 18, which are supported rearwardly of the presser-bar on 75 rods 19 adjustably secured in the cross-bar 2 by screws 20, are connected by links 21 with ball-studs 22 rising from the sole portions at the heels thereof. The rods 19 are spaced equal distances on opposite sides of 80 a vertical plane through the axis of the presser-bar and parallel with the line of feed. Because of the universal connections at the opposite ends of each of the links 21, the sole portions are each free to tilt in any 85 direction about their ball-and-socket connections 11-12 but are held against rotation in a plane parallel with the plane in which the work advances, as will be apparent from a scrutiny of the drawings. 90

Disposed on opposite sides of a central transverse plane through the presser-foot and through the axis of the presser-bar are a pair of coiled thrust springs 23 whose lower ends bear against the tilting lever 6 95 with a pressure which may be varied by adjustment of the set-screws 24 which constitute an adjustable abutment for their upper ends. These springs 23 normally urge each of the sole portions down upon 100 the work with the same pressure and tend to hold their lower faces in the same plane.

The ball-and-socket connections 11-12 be-

- tween the sole portions and the tilting lever afford extensive bearing surface and enable the sole portions to move or tilt very freely, much more so than in the transverse pin arrangements of the prior art. The tapered connection 7 between the tilting lever and the cross-bar permits wear to be taken up in a simple manner. The coiled springs 17 which normally urge the outside heels of the sole portions yieldingly downward facilitate the introduction of work under the presser and insure a uniform advance of the work at the widely separated needle-holes where the drag of the outlying margins of the body thereof imposes the greatest load on the feeding mechanism. Generally speaking the construction of the present invention is more durable and more efficient than those heretofore in use.
- Having thus set forth the nature of the invention, what I claim herein is:
1. A presser mechanism for sewing machines comprising a presser-bar, a cross-bar secured thereto and having a flat guiding surface in a plane parallel to the axis of the presser-bar, a tilting lever fulcrumed on said cross-bar for movement in parallelism with said flat guiding surface, yielding means between said lever and said cross-bar on opposite sides of their pivotal connection, a pair of sole portions, universal connections between said sole portions and said tilting lever at opposite sides of the latter's pivot, and links for holding said sole portions in relative operating positions.
  2. The combination as specified in claim 1 in which the universal connections between the sole portions and the tilting lever are laterally adjustable.
  3. A presser mechanism for sewing machines comprising a presser-bar, a member fixed to the lower end of said bar and having a pair of angularly disposed flat faces in planes parallel and perpendicular respectively to the axis of the presser-bar, a tilting lever fulcrumed on a conical pivot supported by said member for movement in parallelism with one of said flat surfaces on the member, a pair of sole portions, ball-and-socket connections between said sole portions and said tilting lever at opposite sides of said conical pivot, one of said flat surfaces on said member overhanging said tilting lever and affording stops for limiting its movement, and means for holding said sole portions abreast of each other.
  4. A presser mechanism for sewing machines comprising a presser-bar, a member fixed thereto, a pair of sole portions, a lever fulcrumed intermediate its ends to said member and at its opposite ends having universal connections with said sole portions, spring means interposed between each of said sole portions and said tilting lever normally urging the heel of the sole portions downward, and means for holding said sole portions against rotation in a plane perpendicular to the axis of the pressure-bar and about the universal connections between the sole portions and the tilting lever.
  5. In a presser mechanism for sewing machines, a support, a pair of relatively shiftable sole portions having universal connections with said support, and springs arranged to yieldingly urge the outside heels of the sole portions downward.
  6. In a presser mechanism for sewing machines, a presser-bar, a tilting lever fulcrumed thereon, a pair of sole portions having universal connections with the opposite ends of the tilting lever, and coiled springs urging the outside heels of the sole portions yieldingly downward upon the work.
  7. In a presser mechanism for sewing machines, a presser-bar, a tilting lever fulcrumed thereon, a pair of sole portions having universal connections with the opposite ends of the tilting lever, coiled springs urging the outside heels of the sole portions yieldingly downward upon the work, and means for varying the force or tension of the coiled springs.
  8. In a presser mechanism for sewing machines, a presser-bar, a tilting lever fulcrumed thereon, a pair of sole portions having universal connections with opposite ends of the tilting lever, coiled springs urging the outside heels of the sole portions yieldingly downward upon the work, and stops for limiting the action of the coiled springs in one direction.
  9. In a presser mechanism for sewing machines, a supporting means, a sole portion adapted to bear on the work and having a ball-and-socket connection with said supporting means whereby it may tilt in different directions, and means for preventing the sole portion turning in the plane of the work.
  10. In a presser mechanism for sewing machines, a support, a sole piece having universal connection with said support, whereby said sole piece may tilt in different directions relative to said support, said sole piece being of greater width than length, and means independent of said universal connection for restraining said sole piece against turning in a plane parallel to the plane of the work.
  11. In a presser mechanism for sewing machines, a presser-bar, a tilting lever pivotally connected with said presser-bar, a pair of sole pieces of greater width than length each having universal connection with said tilting lever, and means independent of said universal connections for restraining said sole pieces against turning in planes parallel to the plane of the work.
  12. In a presser mechanism for sewing machines, a support, a plurality of sole-

pieces each having ball-and-socket connection with said support, and means for preventing said sole-pieces turning in the plane of the work.

5 13. In a presser mechanism for sewing machines, a presser-foot support, a presser-foot, a ball-and-socket connection between said presser-foot and its support permitting

universal tilting movements of the presser-foot, and an anchor link connected to said 10 presser-foot for holding the latter against turning movement in the plane of the work.

In testimony whereof, I have signed my name to this specification.

ALBERT H. DE VOE.
